CHARLES J. GLUNZ, OF POTTSVILLE, PENNSYLVANIA.

DIRECTION-SIGNAL FOR AUTOMOBILES.

1,286,995.

Specification of Letters Patent. Patented Dec. 10, 1918.

Application filed May 23, 1918. Serial No. 236,226.

To all whom it may concern.

Be it known that I, CHARLES J. GLUNZ, a citizen of the United States, residing at Pottsville, in the county of Schuylkill and State of Pennsylvania, have invented a new and useful Direction-Signal for Automobiles, of which the following is a specification.

This invention relates to direction signaling devices for automobiles.

The object is to provide a device of this character, which is capable of being readily arranged for operation by either the hand or the foot of the driver, to project into view means for attracting the attention of following automobile drivers or of crossing policemen, or others, and indicate to the same that a turn is about to be made.

Another object is to provide a signaling device which will give the desired signal or warning at night time as well as during the day, the night signaling means including an electric light which is automatically cut out for day use by switching off the usual lighting system of the car, the day signaling means and that constituting part of the night signaling means, consisting of a flag adapted to be unfurled and simultaneously uncovered and allowed to flutter in the breeze to attract attention, or to be rolled up and withdrawn from view within a housing, upon the manipulation of the operating means.

A further object is to construct a device for such purpose, having few parts to become deranged and which may be readily installed in a car upon the inner wall of the body thereof, to one side and in advance of the operator, so as to occupy a minimum amount of space and to be readily accessible for operation.

A full and complete understanding of the invention may be obtained from a consideration of the following detailed description, taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the appended claims.

In the drawing, in which like reference

characters designate corresponding parts throughout the several figures:

Figure 1 is a perspective view illustrating the device of the present invention in installed position in the body of a car; 60

Fig. 2 is a horizontal sectional view through the flag housing and showing the means for supporting the same;

Fig. 3 is a vertical, longitudinal sectional view, taken on the line 3-3 of Fig. 2 and 65 looking in the direction of the arrow;

Fig. 4 is a transverse sectional view, taken on the line 4-4 of Fig. 3;

Fig. 5 is a detail perspective view of the supporting bracket for the flag housing; 70

Fig. 6 is an end elevation of the same;

Fig. 7 is a detail view of the keeper for the operating lever of the device.

The improved signaling device of the present invention is illustrated in Fig. 1 75 of the drawing as being installed in the left hand side of the car, and adjacent to the dash, but it will, of course, be understood that in some cars the same may be located at the opposite or right hand side thereof, 80 depending upon the make of the car and the rules governing traffic where the car may be used. It will furthermore be observed that the flag housing 1 is shown as being attached to the windshield of the automobile, but I 85 do not wish to be limited to such arrangement, as the said housing, together with the parts carried thereby, may be equally well attached to the side of the car, upon the outside thereof, and adjacent to the top of the 90 same; so that the flag will be readily observed, when unfurled, in a manner to be explained. In addition to this, it will be seen that the operating means for the device is shown as consisting of a foot lever, 95 but it will be readily granted that the same may be in the form of a hand lever and so located as to be within easy reach of the hand of the driver of the car.

The flag housing 1 consists of a semi-cylindrical casing of sheet metal, of a length sufficient to cover a flag 2 of suitable dimensions, when the same is rolled upon a spring-actuated roller 3, as will become apparent, the sides of the semi-cylindrical casing extending somewhat below the rolled flag 2, so as to exclude rain, snow, etc., and otherwise protect the same.

The housing 1 is arranged at right angles to the length of the car and is adapted to 110

2
extend outwardly from the side thereof, so that the flag 2, when unfurled, may be readily seen from in front of the car, as, for instance, to signal to a crossing police man, or to others, or may be visible from the rear to caution following cars that a turn is about to be made.

10 The housing 1 is provided, at its outer end with an end wall 4, having a suitable aperture for the reception of a rectangular spring-winding pindle 5, which is connected to a spring 6, in the ordinary manner, the spring 6 being mounted within the roller 3 for normally winding the flag 2 thereon, 15 while the opposite or inner end of the roller 3 is provided with the usual round pindle 7 mounted to freely rotate in the upper end of an extension 8, which is riveted or otherwise secured to a supporting bracket 9. 20 The supporting bracket 9 is formed of suitable sheet metal formed into a flat horizontally-disposed platform 10, and a vertically-disposed inner wall 11, to which the said extension 8 is secured. At one end, the 25 bracket 9 is provided with a curved clamping member 12, adapted to coat with a detachable and adjustable clamping member 13, through the medium of a clamp nut 14, for securing the bracket 9 to the windshield 30 of the automobile, as will be readily understood. The bracket, together with the extension 8 and the clamping member 12, may, however, be formed of a single casting, if preferred.

35 The housing 1 is provided, at its inner end, with outwardly extending flanges 15, which are adapted to be riveted, or otherwise secured to the platform 10 of the bracket 9 to support the housing and the parts carried thereby in extended, horizontal position.

40 The major portion of the winding roller 3 is of sufficient diameter to cause the complete winding of the flag 2 thereon, upon 45 two or three revolutions of the said roller, while the inner end of the latter is reduced, as indicated at 16, for the reception of an actuating strap 17, formed of leather, canvas or the like, which is adapted to be wound 50 thereon and to have its free end pulled, in a manner to be explained, to cause the rotation of the roller against the action of the spring 6 and the simultaneous unwinding of the flag 2. By reducing the diameter of the 55 roller, as at 16, where the strap 17 is attached, the amount of longitudinal movement imparted to the strap necessary to completely unwind the flag, is reduced, as will be readily understood.

60 The free end of the strap 16 is connected to a chain 18, or other flexible connection, which extends downwardly and is attached, at its lower end, to an operating lever 19, at an intermediate point of the latter. The 65 lever 19 is shown in the form of a foot lever

having a treadle portion 20 for the engagement by the foot of the driver, while the forward end of the lever is fulcrumed to a bracket 21 secured to the dashboard of the car. The said lever may, however, as has 70 been stated, consist of a hand lever attached in any convenient manner and location.

75 The lever 19 is adapted to move in an up-and-down movement, adjacent to the inner side of the wall of the car, and to be guided in a keeper 22 attached thereto, the pressure of the foot of the operator causing the lever to be lowered, while the spring 6 within the roller 3 will act to elevate the lever and wind up the flag, when the lever is released. 80 A leaf spring 23, secured to the inner side of the keeper 22, engages over the top of the lever when the latter is depressed, and serves to hold the same down to allow the operator to use his feet otherwise, and the 85 said lever will remain in its depressed position, held by the spring 23, until it is kicked loose or otherwise released.

90 Upon the inner wall of the car, at a point intermediate of the ends of the foot lever 19, and in its path of swinging movement, there is located a plate 24 provided with a pair of contact points 25 and insulated from the side of the car, as indicated at 26, the said contact points 25 being adapted to be 95 bridged by a conductor plate 27 carried by the lever 19 and insulated therefrom, as at 28, when the said lever is in its lowered position.

99 At the outer end of the housing 1 and 100 upon the top thereof, there is located an electric lamp of the two-way type, adapted, when lighted, to throw rays of light forwardly in advance of the car and backwardly at the same time. The lamp 29 is 105 secured centrally of the housing by a suitable clamp nut 30, the electrical connections 31 leading therefrom, passing through the clamping means and being secured to the underside of the housing 1 and upon one side 110 thereof by spring clips 32, which are open at one end to permit of the detachment of said conductors 31 when desired. The flag winding roller 3 is arranged to one side of 115 the center of the housing 1 in order to prevent any interference of the flag with the connections 31 or the clips 32.

120 One of the connections 31 leads directly to one of the contact points 25, while the other connection 31 may be grounded upon the body of the automobile, or otherwise included in the ordinary lighting system of the car. The other contact point 25 is connected by a conductor 33, which may also be included in the lighting system in the ordinary manner.

125 The flag 2 is preferably triangular in shape in order to facilitate its winding upon the roller 3, as will be understood, and is weighted at the lower point, as indicated at 130

34, to insure its unwinding action when the roller is actuated by pressure of the foot upon the lever, and the flag is preferably made of durable material, of some color 5 designating danger, such as red, so as to more readily attract attention.

By reason of the fact that the flag is attached to the roller along its upper edge alone, the said flag is free to flutter in the 10 breeze caused by the moving automobile and by its movements, the eye is more readily attracted than if the flag were held stationary.

In the operation of the device, the driver, upon approaching a corner where he may 15 wish to turn to the left, has only to press the lever 19 with his foot when the lever will be retained by the spring 23 and the flag 2 brought to view and, if at night, the lamp 29 caused to light up both sides of the flag 20 and to throw rays in advance and in rear thereof. If, however, it is daytime, the flag alone will suffice as a signal, since the light is automatically cut out when the lighting 25 system of the car is cut out, which is usually done in the daytime. The foot may then be used to operate the brakes, etc., without the necessity of paying any further attention to the signal, until the turn is made, when by 30 simply pressing or kicking the lever out of its engagement by the retaining spring 23, the said lever, through the action of the winding spring 6 will be elevated and the flag wound upon the roller, ready for another operation.

35 From the foregoing, it is thought the merits of the invention will be appreciated, and it will be seen that a simple, durable and easily operated signaling device for automobiles has been provided, that may be 40 cheaply manufactured, sold at a low cost and easily installed in any make of car.

What is claimed is:

1. A direction signal for automobiles, comprising a signal-housing adapted to be secured in position to project from the side of the car, a winding roller mounted for rotation beneath the housing, a signal flag attached to the roller and adapted to be wound thereon, said flag when unfurled depending from the roller so as to flutter in the air, a flexible connection wound upon a portion of the roller and extending down within the body of the car, and a lever mounted for up-and-down movement within the body 55 of the car and connected to the lower end of the flexible connection.

2. A direction signal for automobiles, comprising an elongated, semi-cylindrical signal housing, arranged to shed water and having 60 means whereby it may be secured in later-

ally projecting relation to the side of the car, a spring-actuated winding roller mounted to rotate beneath the housing and longitudinally thereof, a signal flag wound upon a portion of the roller and adapted when unfurled to depend therefrom so as to flutter in the air, said roller having a portion extending inwardly beyond the flag, a flexible connection wound upon said extended portion of the roller, a lever mounted within the car and beneath the inner end of the roller and having connection with the said flexible connection, whereby the said roller may be actuated.

3. A direction signal for automobiles comprising a housing formed of sheet metal of semi-cylindrical form, arranged convex side up and disposed transversely to the car, an end wall formed at the outer end thereof and having a bearing, outstanding flanges 80 carried by the inner end thereof, an angular bracket having a horizontally-disposed platform adapted to have the flanges of the housing secured thereto and provided with coacting jaws for clamping to the windshield of the automobile for securing the housing in laterally projecting position, a bearing carried by said bracket and in alinement with the first-named bearing, a spring-actuated roller mounted for rotation in the bearing 85 and having a reduced inner end, a flag wound upon the larger portion of the roller, a lever mounted for up-and-down movement within the car beneath the inner end of the roller and a flexible connection having its 90 upper end portion normally wound upon the reduced portion of the roller and connected at its lower end to the said lever.

4. A direction signal for automobiles comprising a signal housing, means for securing 100 said housing in outstanding relation to the side of the car, a horizontal roller mounted longitudinally of the housing and transversely of the car, a signal flag wound upon said roller adapted to depend from the roller when unwound and to flutter in the air, means of weighting the free end of the flag, means for normally winding the flag upon the roller, a vertically movable lever mounted within the car, and a flexible connection 105 with the roller to unwind the flag against the action of the winding means.

In testimony that I claim the foregoing as my own I have hereto affixed my signature in the presence of two witnesses.

CHARLES J. GLUNZ.
